UNITED STATES PATENT OFFICE

MAURICE SAMBURG, OF BROOKLYN, NEW YORK, ASSIGNOR TO LOCK PATENTS HOLDING CORPORATION, OF NEW YORK, N. Y., A CORPORATION OF NEW YORK

LOCK

Application filed November 8, 1928. Serial No. 317,940.

This invention relates to lock construction. More particularly it relates to a combination controlled lock.

An object of this invention is to provide an improved lock of the character described having means for positive attachment to a screw threaded shank and combination controlled means for preventing or permitting removal of the lock from said shank.

10 A further object of this invention is to provide a simple and highly efficient means for changing the combination of the lock.

Another object is to provide a rugged, compact burglar-proof lock of the character described which shall be cheap of manufacture, 15 easy of operation and yet practical and efficient to a high degree.

Among the dominant features of the invention as will hereinafter more fully appear, 20 is that the lock may be applied wherever a bolt or any screw threaded member is available in connection with the article or device to be locked or safeguarded, the mechanism being such that when in locking condition, 25 the device as a whole can be freely rotated about such a bolt or threaded member without unscrewing said device so that forcing the same cannot be effective to break parts away to thus cause unlocking.

30 Other objects of this invention will be in part obvious and pointed out in part hereinafter.

The invention accordingly consists in the features of construction, combinations of elements, and arrangement of parts which will be exemplified in the construction hereinafter described, and of which the scope of application will be indicated in the following claims.

40 In the accompanying drawings, in which is shown one of the various possible illustrative embodiments of this invention:

Fig. 1 is a longitudinal cross-sectional view of a lock; embodying the invention.

45 Fig. 2 is a cross-sectional view taken on line 2—2 of Fig. 1;

Fig. 3 is a cross-sectional view taken on line 3—3 of Fig. 1;

50 Fig. 4 is a cross-sectional view taken on line 4—4 of Fig. 1 showing the position of

the parts of the lock when the latter is set with the proper combination;

Fig. 5 is a cross-sectional view similar to Fig. 4 showing the position of the parts with the lock set to the proper combination and the splining mechanism actuated;

Fig. 6 is a cross-sectional view similar to Fig. 4 showing the position of the parts with the lock set for changing the combination; and

Fig. 7 is a partial top plan view of the lock 60 with parts of the cover broken away to show the interior construction.

Referring in detail to the drawings, 10 designates a lock embodying the invention. Said lock generally described, comprises a nut member 11 having an internally threaded portion 11a, housed within a cylindrical casing 12, and mechanism 13 also housed within said casing for splining said nut to said casing. The splining mechanism 13 is controlled by combination mechanism 14. As will more fully appear hereinafter, the nut 11 may be splined to the casing 12 only when the proper combination is set, the entire 70 mechanism thereafter acting as an integral nut for screwing on or unscrewing from any suitable threaded shaft (not shown). Once the lock has been attached to such a shaft, the nut may be unsplined from the casing. The 75 combination may then be upset and the casing can thereafter be turned in any direction without unscrewing the nut 11. Thus the device cannot thereafter be removed without setting the proper combination or unlocking 80 with key to permit the splining movement.

Proceeding now with the more detailed description of the device, the nut 11 is seen to comprise a cylindrical portion 15 and an outwardly extending annular flange 16 loosely fitting the interior surface 17 of said casing 12. An annular ring 18 may be interposed between the cylindrical portion 15 of the nut 11 and the casing 12, said ring being secured to said casing in any suitable manner, as by screws 19. Said ring 18 abuts the flange 16 to retain the nut 11 in the casing. The abutting surface 20 of said flange and ring may be formed with complementary annular grooves 21 receiving ball bearings 22 to 95 100

ensure smooth relative rotation between the casing and the nut.

A portion of the nut 11 at the flanged end thereof is formed with a smooth central bore 25 communicating with the threaded opening 11a. The flange 16 is also formed with a transverse groove 26 of rectangular cross-section intersecting the bore 25.

The mechanism 13 for splining the nut 11 to casing 12 includes a member 27 comprising a cylindrical or tubular portion 28 coaxial with the casing 12 and terminating in an annular flange 29 fitting the interior surface 17 of said casing. Said member 27 is fixed to casing 12 as by screws 30 extending thru casing 12 and flange 29. Said flange 29 is provided with a transverse groove 31 of rectangular cross-section similar to groove 26 in flange 16, but substantially twice as deep as said groove 26.

The cylindrical portion 28 of member 27 terminates in a reduced portion 32 ending a short distance from an end wall 33 formed integrally with said casing 12.

Said member 27 is formed with an axial bore 35 extending therethru wherein is mounted for rotation within said bore 35, cylindrical rod 36 having an end portion 37 extending beyond said reduced portion 32. An actuating handle 38 for rotating said rod 36 is mounted on said end portion 37 by a pin 39 extending thru said end portion and thru a collar portion 40 formed integrally with said handle.

The opposite end portion 41 of said rod 36 extends across groove 31 and into bore 25 formed in the nut 11, and is formed with a shallow helical peripheral groove 42. Loosely mounted on said end portion 41 is a key or spline member 43 of rectangular cross-section, and substantially fitting within the groove 31 formed in flange 29. The width of said key 43 is substantially equal to the depth of said groove 31, to permit relative rotation between flange 29 and flange 16. Said key member 43 is mounted for axial movement on said rod 36. To this end said key 43 is provided with a small projection 44 extending into said helical groove. It will now be apparent that rotation of the rod 36, by actuation of handle 38, will shift the key to the left or right depending upon the direction of rotation of said handle. When grooves 31, 26 are aligned, clockwise rotation of handle 38 as seen in Fig. 3 will move the key 43 to the right as seen in Figs. 1 and 7 to spline the nut 11 to the member 27 and consequently to the casing 12 to which said member 27 is rigidly secured. Small coil compression springs 45 housed in pockets 46 in said key 43 abut face 47 of flange 29 and urge said key 43 toward groove 26 to thus facilitate the splining movement. Obviously, rotation of the handle 38 in the direction opposite to that just described will move the key to the

left until it is entirely contained in groove 31 and thus said key clears the flange 16. In this position the nut 11 cannot be removed from a screw threaded shank to which it may be secured since said nut cannot be rotated for the unscrewing movement.

The combination control mechanism 14 for preventing rotary movement of rod 36 and for releasing said rod for actuation, is housed within the casing 12. Access to said mechanism and to handle 38 for manipulation may be had thru a door member 50 forming part of casing 12. Said door member 50 comprises a substantially semi-cylindrical portion 51 and an end wall portion 52 flush with end wall 33 of the casing and forming part thereof, and preferably hinged to the casing along a longitudinal edge 53 of the semi-cylindrical portion of said door. A small protuberance 54 on the surface of the casing edge 55 adjacent the edge 56 of the door opposite to the hinged edge 53, provides friction means for maintaining said door shut.

Mounted on the reduced portion 32 of cylindrical member 28 is an annular member 60 having a flange 61 extending from said member toward end wall 33 of the casing. Said flange is in the plane of the handle 38, but is shaped to an arc of only about 120° thus permitting limited rotation of said handle. Said member 60 is secured to casing 12 in any suitable manner (not shown).

The handle 38 may be provided with a projection 62 extending toward member 60. Said projection 62 is notched as at 63 to serve as an index for the combination numbers as will hereinafter appear. A small circular plate spring 64 may be secured at one end portion 65, as by rivet 65a, to the member 60, adjacent flange 61. Said spring extends between handle 38 and said annular member 60 and terminates in an extension 66 symmetrical to end portion 65. Said spring is further provided with an outward projection 67 having an edge 68 adjacent the handle 38 when said handle is in a central position as shown in full lines in Fig. 3. Said projection 67 prevents counterclockwise rotation (looking at Fig. 3) of the handle 38 except when the finger pressure applied to extension 66 moves the spring 64, and consequently the projection 67 formed therewith, toward the annular member 60 to enable said handle to clear said projection.

Loosely mounted for rotation on the tubular member 28 are three similar rings 70. Interposed between said rings may be washers 71 provided with lugs received in a longitudinal keyway 73 formed in the outer surface of tube 28. Said rings 70 and washers 71 extend between annular member 60 and flange 29. Mounted on ring members 70 are similar wheels 75 formed with spaced radial projections 76. Each wheel is preferably formed with ten of said projections 76 bear-

ing the ten digits consecutively. Rotating the wheels 75 will obviously change the combination of members in alignment with index 63 when the handle 38 is centrally positioned.

Means is provided for releasably locking the rod 36 and the rings 70 to the tube 28. To this end, said rod 36 is formed with a longitudinal groove 77 which terminates short of the helically grooved end 41 of said rod 36.

The cross-sectional curvature of groove 77 conforms to the curvature of a cylindrical pin 77a overlapping said rings 70 and slidably received in a slot 77b formed in tube 28. The diameter of pin 77a is such that when said pin lies in groove 77 the outermost portion thereof is in line with the outer peripheral surface of tube 28, to permit rotation of rings 70 with respect to said tube (see Fig. 4). Each of rings 70 is formed with a notch 79 in the inner periphery thereof, substantially similar in cross-section to groove 77. Thus when all three rings are in such position that the three notches 79 are in alignment with slot 77b and groove 77, rotation of rod 36 is possible since the pin 77a simply slides upwardly into said notches as seen in Fig. 5. Washers 71 are notched similarly to rings 70 in alignment with slot 77b, as at 80, to permit this movement of the pin 77a.

Means is provided for releasably locking said rings 70 to wheels 75. To this end said rod 36 is formed with a longitudinal groove 78 substantially diametrically disposed to groove 77. The cross-sectional curvature of said groove 78 conforms to the curvature of a pin 78a overlapping said rings 70 and slidably received in a slot 78b formed in said tube 28. The diameter of said pin 78a is substantially equal to the thickness of tube 28. (See Figs. 4 and 5.) Said pin 78a is adapted to coact with small pins 81 mounted in each of rings 70 for radial sliding movement. Each pin 81 comprises a head portion 82, received in a radial cylindrical recess 83 formed in each of said rings, and a shank portion 84 received in an opening 85 communicating with each of said recesses. Light compression springs 86 are interposed between said heads 82 and the bottom walls 87 of said recesses 83. The wheels 75 are each formed with a sinuous inner peripheral portion 88 providing notches 89 aligned with each projection 76, and shaped to receive the heads 82 of pins 81 when the pin 78a is forced into slot 78b, as seen in Figs. 4 and 5. The angle between recess 83 and notch 79 in each ring 70 is equal to the angle between slots 77b and 78b; so that when notches 79 are aligned with slots 77b, pins 81 will be aligned with slots 78b.

The operation of the device will now be described. Beginning with the position of the parts as shown in Fig. 4, the handle 38 is

there shown in central position. In this position the head 82 of each pin 81 projects into a notch 89 of each wheel 75 and thus the wheels 75 are all locked to rings 70 thru said pins 81. Rotation of said locked wheels and rings is now permitted since groove 77 is aligned with slot 77b and therefor receives a portion of pin 77a. Such rotation of the wheels brings different combination of numbers in alignment with notch 63 in handle 38. The true combination is arrived at when the notches 79 are all in alignment with slot 77b. This combination must be known by the user of the lock. The wheels 75 are set for the true combination of numbers as described above, the handle 38 may be rotated in a clockwise direction, bringing the parts from the position shown in Fig. 4 to that shown in Fig. 5. During this movement the pin 77a is forced out of groove 77 and into the groove formed by the aligned notches 79 and 80. This movement of the handle 38, of course, causes splining of nut 11 to the casing 12 as is explained in detail above. To carry out this splining movement it may be necessary to rotate the casing relatively to the nut so that grooves 26, 31 register. When the parts have been splined the casing and nut may be screwed on or off a suitably threaded shank, such as a bolt shank, to lock any parts together that may be bolted together. To prevent the nut from being removed, the handle 38 is moved back to the central position to unspline the casing from the nut, and the wheels are moved in any direction to upset the true combination. Rotation of the casing by anyone does not affect the nut which consequently cannot be unscrewed.

The true combination for removing the lock may be changed. To this end, the spring 64 is pushed toward annular member 60 for applying pressure to the end portion 66 of spring 64 until projection 67 clears the handle 38. The handle may then be turned in a counterclockwise direction bringing the parts from the position shown in Fig. 4 to the position shown in Fig. 6. The wheels must first be set for the old true combination of numbers (Fig. 4) before the new true combination may be set, since handle 38 cannot be rotated at all unless notches 79 are aligned with slot 77b.

In the position shown in Fig. 6, groove 78 is aligned with slot 78b and pins 81 to permit wheels 75 to be turned with respect to ring 70. During such rotation the curved portions 90 of the wheel 75 between the notches 89 may force the pins 81 into slot 78b against the pressure of compression springs 86. This action is possible since the pins 81 may now force the pin 78a into groove 78, a sufficient distance to permit bringing the outer portions of heads 82 in alignment with the outer peripheral surface of rings 70.

During this rotation of wheels 75, the rings 70 are locked to tube 28 since pin 77a has been forced out of groove 77 and into notches 79, and 80. The wheels may now be set at the new desired combination of numbers. When this is done, the handle 38 is moved back to the central position of Fig. 4, and the wheels 75 are again locked to the rings 70.

It will be understood that any number of 10 wheels and complementary rings may be used, three of each being here shown for the purpose of illustration only.

Means other than combination mechanism 15 may of course be used to control the movements of rod 36.

It will thus be seen that there is provided 20 a device in which the several objects of this invention are achieved, and which is well adapted to meet the conditions of practical use.

As various possible embodiments might be 25 made of the above invention, and as various changes might be made in the embodiment set forth, it is to be understood that all matter herein set forth or shown in the accompanying drawings is to be interpreted as illustrative and not in a limiting sense.

Having thus described my invention I 30 claim as new and desire to secure by Letters Patent:

1. In a lock, in combination, a housing, an internally threaded member mounted within 35 said housing for relative rotation thereto, and means for releasably locking said member to said housing, said means including a key and a member having a helical groove engaging said key for axially moving said key as said grooved member is rotated.

2. In a lock, in combination, a housing, an 40 internally threaded member mounted within said housing for relative rotation thereto, means for releasably locking said member to said housing, said means including a key and a member having a groove engaging said key for axially moving said key as said groove member is rotated, and combination mechanism for controlling rotation of said member.

3. In a lock, in combination, a casing, an 45 internally threaded member mounted within said casing for relative rotation therewith, and means for releasably locking said member to said casing, said means including a key transversely disposed relative to said member, and a member coaxial with said threaded member having a groove engaging said key for longitudinally moving said key upon rotating said grooved member.

4. In a lock, in combination, a casing, a 50 screw threaded nut member mounted on said casing for rotation thereon, said member being provided with a transverse groove, a grooved member secured to said casing, a key member movably received within said 55 grooves, and combination mechanism within

said casing for controlling movement of said key member.

5. In a lock, in combination, a cylindrical casing, a nut member mounted for rotation within said casing, said member being provided with a transverse groove, a grooved member secured to said casing, a key member receivable within said grooves, means for moving said key member with relation to 70 said grooves to key said nut member to said 75 casing for rotation therewith, and combination mechanism for controlling the operation of said moving means.

6. In a lock, in combination, a casing, a member mounted for rotation within said casing, 80 said member being provided with a transverse groove, a member transversely disposed with respect to said casing secured to said casing, said member having a groove parallel to and registering with said first groove, a 85 key member receivable within said grooves, a member coacting with said key member for moving said key member transversely within said grooves and axially of said casing to key said first member to said casing for rotation therewith, and combination mechanism for controlling the operation of said 90 second mentioned member.

7. In a lock, in combination, a cylindrical casing, a nut member mounted for rotation 95 within said casing, said nut member being provided with a transverse groove, a grooved member secured to said casing, a key member receivable within said grooves, and a helically grooved member coacting with said key 100 member for longitudinally moving said key member with respect to said grooves to key said nut to said casing for rotation therewith, said grooved member forming a bearing for rotatably mounting said helically grooved 105 member coaxially with said casing.

8. In a lock, in combination, a cylindrical casing, a nut member mounted for rotation within said casing, said nut member being provided with a transverse groove, a grooved member secured to said casing, a key member receivable in said grooves, a helically grooved member coacting with said key member for longitudinally moving said key member with respect to said grooves to key said nut to 110 said casing for rotation therewith, said grooved member forming a bearing for rotatably mounting said helically grooved member coaxially with said casing, and actuating means attached to said helically grooved 115 member at one end thereof.

9. In a lock, in combination, a cylindrical casing, a nut member mounted for rotation within said casing, said nut member being provided with a transverse groove, a grooved member secured to said casing, a key member receivably in said grooves, a helically grooved member coacting with said key member for longitudinally moving said key member with respect to said grooves to key said 120 125

nut to said casing for rotation therewith, said grooved member forming a bearing for rotatably mounting said helically grooved member coaxially with said casing, actuating 5 means attached to said helically grooved member at one end thereof, and combination controlled mechanism mounted on said grooved member between said actuating means and said spline for preventing operation of said actuating means.

10. In lock construction, in combination, a cylindrical casing having an open end, a member rotatably mounted within said casing, means secured to said casing for preventing removal of said member thru said open end, means within said casing for keying and unkeying said member to said casing, and combination controlled mechanism within 15 said casing for preventing and permitting 20 said keying and unkeying operation.

11. In a lock, in combination, a housing, a member rotatably mounted within said housing, and formed with a groove, a member fixed to said housing formed with a groove 25 registering with said first groove, said second member having a tubular portion, a key within said grooves adapted to key said members together and means for moving said key into 30 keying position, said means comprising a shaft journalled within said tubular portion and means on said shaft for moving said key as said shaft is rotated.

12. In a lock, in combination, a housing, a member rotatably mounted within said housing, and formed with a groove, a member fixed to said housing formed with a groove registering with said first groove, said second member having a tubular portion, a key within 35 said grooves adapted to key said members together and means for moving said key into keying position, said means comprising a shaft journalled within said tubular portion, means on said shaft for moving said key as said shaft is rotated, and combination mechanism 40 for locking said shaft to said tubular portion.

13. In a lock, in combination, a housing, a member rotatably mounted within said housing, and formed with a groove, a member fixed to said housing and formed with a groove registering with said first groove and having a tubular portion, a key within 45 said grooves adapted to key said members together and means for moving said key into keying position, said means comprising a shaft journalled within said tubular portion, means on said shaft for moving said key as said shaft is rotated, a handle fixed to said shaft for rotating the same, and means for 50 limiting the angular movement of said handle.

14. In a lock, in combination, a housing, a member rotatably mounted within said housing, and formed with a groove, a member fixed to said housing formed with a 55

groove registering with said first groove, and having a tubular portion, a key within said grooves adapted to spline said members together and means for moving said key into keying position, said means comprising a shaft journalled within said tubular portion, means on said shaft for moving said key as said shaft is rotated, said portion having a longitudinal slot therein, said shaft having a longitudinal groove formed therein, and a pin mounted within said slot and having a portion partially received within the groove in said shaft for locking said shaft to said portion.

15. In a lock, in combination, a housing, a member rotatably mounted within said housing, and formed with a groove, a member fixed to said housing and formed with a groove registering with said first groove, and having a tubular portion, a key within said grooves adapted to spline said members together and means for moving said key into keying position, said means comprising a shaft operatively associated with said key and journalled within said tubular portion, a plurality of rings on said tubular portion, said portion having a longitudinal slot therein, said shaft having a longitudinal groove formed therein, each of said rings having a notch formed on the inner periphery thereof, and a pin mounted within said slot and having a portion received within said last mentioned groove for locking said shaft to said portion, when said rings are positioned with said notches unaligned with said slot, said pin being movable upon positioning said rings for aligning all of said notches with said slot, out of said groove and into said aligned notches to permit rotation of said shaft with respect to said portion, and to lock said rings to said portion.

In testimony whereof I affix my signature.
MAURICE SAMBURG.
